UNITED STATES PATENT OFFICE

144,877

DESIGN FOR A LAMP OR SIMILAR ARTICLE

Edward V. Sundt, El Monte, Calif.

Application October 6, 1945, Serial No. 122,600

Term of patent 14 years

(Cl. D26—8)

To all whom it may concern:

Be it known that I, Edward V. Sundt, a citizen of the United States, residing in the city of El Monte, in the county of Los Angeles, State of California, have invented a new, original, and ornamental Design for a Lamp or Similar Article, of which the following is a specification, reference being had to the accompanying drawing, forming a part thereof.

In the drawing:

I claim:

The ornamental design for a lamp or similar article, as shown.

EDWARD V. SUNDT.
